U. Ward

Brick Machine.

Patented Dec. 15, 1835.

Ulysses Ward of Washington City D. C.
Letters Patent.

The Schedule referred to in these Letters Patent and making part of the same containing a description in the words of the said Ulysses Ward himself of his improvement in the machine for pressing and delivering bricks and other substances.

To all to whom these presents shall come: Be it known that Ulysses Ward of the City of Washington and District of Columbia have invented a new and useful improvement in the machine of Pressing and delivering Bricks according to the plan set forth by Nathan Gauray in his Patent bearing date on the 8th of April Eighteen Hundred & Thirty five, May said improvement not being confined to the manufacture of bricks but intended to be used for all substances or composition of matter requiring to be so pressed and delivered, such as, Hay, Cotton &c. My object is to simplify his construction in the pressing part so as to dispense with the combination of wheels, by which he conducts the power from the power from the main axle or crank to the shaft containing the cams, and also the lever by which he conveys the power from them to the rods communicating with the moulds below. I also simplify the delivering part by making an omission of the same, pistons and apertures in the place thereof an arrangement near the lower part of the pressing piston which I shall proceed to describe. It would have it understood that the pressing process, which I simplify, is not that effected by the downward motion of the pressing piston, that being done by the crank and toggle joints, which I do not teach, but I speak of that pressure which he can produce by raising from below so as to cause the follower of the mould to meet the piston, which effect according to my plan by first cutting the sliding rods communicating with the mould, follow at a point just above the top bar by which they are guided in their passage up and down, this end thus cut off I bend now towards the pressing piston so as to form a spear whose head is intended to receive (as a catch) the end of a short bar which I place horizontally extending from said shoulder to the pressing piston where it again catches upon a small knot or cog projecting from the side of the said piston, & which may be on merced length of the pivot forming a part thereof. The lever I support at its proper height above the top bar so as to be means of a perpendicular inserted there for that purpose having a pivot on which said lever is to turn. The piston in descending strikes by the cog against one end of the lever and carries it down the other which is under the catch or shoulder on the sliding rods is consequently made to

be it up until released from the cog at the piston this of course brings up the follow in the mould, which is connected with the rods, and meets the pressure on top of the bricks which will be found a great advantage in the manufacture. But that upon which I attach the greatest value is the manner I desire to raise the follow, after the pressm is accomplished in order to deliver the finished brick from the mould, which I thus perform. Beneath the top bar already mentioned in which the rods slide up and down, I place another horizontal bar from one to the other, and secure thereto so as to move with them which with that at the bottom of the same stand for the follow, constitutes a frame to be raised by a contrivance attached to the fast of these two horizontal bars consisting of an excavation in the lower side in which I place between the piston and rods a spring (a spiral one answers well) having secured to the end next the piston a wedge so that it shall slide in this way as the spring contracts or dilates, a similar one occupies the other side of the piston. Now through the horizontal bar is formed a hole for the passage of the piston, & at the edge there of these sliding wedges rest when the spring is contracted to its usual extent though projecting inward sufficiently to render it necessary that they should recede before the piston can descend, or in other words they constantly press against its sides so that when the descent has been sufficient to effect the purpose and the piston raised enough to free it from the brick, a notch or shoulder cut into the sides of the piston opposite to the wedges allows them to enter by the dilation of the spring and consequently (for the time) raises the horizontal bars and rods with the piston until the brick is delivered at the proper height, when the wedges come in contact with the two other stationary ones attached to the lower side of the top stationary bar, through which the rods slide and applied close to the ^{edge of the} piston so that as they are ministered between them and the sliding wedges when arrived at the required altitude which of course loosens their hold, the frame and horizontal bars fall to their proper situation, leaving the mould open for another charge of clay. This method of delivery I call the first and esteem it the best, but have another mode of application to produce the same result, this instead of springs and wedges and notch in the piston I simply continue the cog or knot mentioned in the joint, so as to form a long bar having the ends of a triangular shape, with one edge pointing downwards, the top side to be horizontal. These are brought directly over the short-ened rods which instead of the shoulder ^{notch} already described have the top fastened into the shape of two shoulders upon elastic shanks placed on opposite sides, and with such a gradual diminution towards the top as to allow the triangular edged edge in descending with the piston to enter between them and displace or spread them over to pass through when

by their elasticity they close and prevent the shoulders to the horizontal top which is done at that time the pressing is effected, when by the return upwards of the piston the long bar brings the rods with it and consequently delivering the brick as before. But to produce the fall of these rods they must be released from the bar. Which is done by means of a bar at each side of the upright of the frame enclosing the machinery and directly over the ends of the rods a projection having on its under surface a wedged shape of sufficient width to force open the tops of the rods so as to release the bar when it immediately falls as before and presents the mould for a fresh charge. It will be seen that by this second method I do not press from below but simply deliver the brick, which I principally aim at (by the means above described) as a much more simple method than that used by the said Ashton Sawyer and thereby making a very considerable diminution in the expense. What I claim as my invention is not previously known in the above described improvement & for which I ask letters Patent is simply the manner of construction by which I effect the delivery of the Brick in the return of the piston itself by the instrumentality of the springs & wedges attaching the mould frame thereto and the manner of releasing it by the wedges, as set forth in the first mode of application, also I claim the second described mode of application consisting of the arrangement of the triangular ended bar working into the elastic catches as described to produce the same effect of delivering as the first mode. Finally, the mode of construction I used in the first method to produce a pressure from below the mould by the arrangement of piston and its communication from the piston to the rods as shown.

In testimony that the above is a full description of my improvement as invented by me I have hereunto set my hand this twenty first day of November in the year 1835.
